UNITED STATES PATENT OFFICE.

PERCY R. FOSTER, OF BROOKLYN, NEW YORK, ASSIGNOR TO MARSHALL T. DAVIDSON, OF SAME PLACE.

STEAM-ENGINE VALVE.

SPECIFICATION forming part of Letters Patent No. 398,777, dated February 26, 1889.

Application filed June 26, 1888. Serial No. 278,213. (No model.)

To all whom it may concern:

Be it known that I, PERCY R. FOSTER, a citizen of the United States, residing in Brooklyn, in the county of Kings and State of New York, 5 have invented certain new and useful Improvements in Steam-Engine Valves, of which the following is a specification.

My invention relates to steam-engine valves, and more especially to the valves of that character of pumping-engine known as "direct-acting duplex engines," composed of two separate and distinct engines capable of being coupled together through the medium of their valves; and my invention consists in the peculiar construction and arrangement of the valves and their connections to facilitate the coupling and uncoupling of the same, as fully set forth hereinafter, and as illustrated in the accompanying drawings, in which—

20 Figure 1 is a transverse section showing the steam-chest, cylinders, and connections of a direct-acting duplex engine, the two parts of which are marked, respectively, No. 1 and No. 2. Fig. 2 is a side view of one of the engines. 25 Fig. 3 is an enlarged section showing the steam-chests and connections. Fig. 4 is a longitudinal section through the auxiliary chest with the valve removed from its seat. Fig. 5 is a back view of the auxiliary valve and its 30 ports. Fig. 6 is a bottom view of the main valve. Fig. 7 is a longitudinal section through the bottom of the main chest.

B B' are the main-valve chests of a pair of engines, which valve-chests contain the main 35 sliding and rocking valves A A', to which movement is given, as in the engine described in Letters Patent No. 155,728, granted to II. A. Jamison, October 6, 1874, and with each main-valve chest is combined an auxiliary- 40 valve chest, C, containing an auxiliary valve, which operates in connection with the main valve, as does the auxiliary valve described in Letters Patent No. 293,243, granted to R. W. Hamilton, February 12, 1884. The construction 45 and arrangement of the auxiliary valves in the present case, however, differ essentially from that described in the aforesaid patent to Hamilton. Thus there is a communication through an upper port, f, and two 50 lower ports, a a', between the interior of the main-valve chest and the interior of the sup-

plemental valve-chest C, the said ports extending to a flat valve-face, x, against which fits the flat semicircular valve B³, provided with two ports, n n', which may be brought 55 to coincide alternately with the ports a a'. Each valve B³ is secured to a sliding and rocking shaft, e, extending through a stuffing-box, m, and provided with an arm, f', and slotted to receive the end of a lever, E, by means of 60 which the valve B³ may be brought against its seat to control the passage of steam to the ports a a', or may be carried away from its seat to permit the free passage of the steam to said port, as in the valve described in the 65 said patent of Hamilton.

The arms f' f' of the two engines are connected to be operated together from some moving part of said engine in the same manner shown in Fig. 1, as the supplemental valves 70 are operated in the engine described in said patent to Hamilton. In working the engines independently—as, for instance, the engine No. 1—when the same has completed its stroke, the main valve A is brought to a closed 75 position and is also oscillated until the steam-ports a b and cove c coincide, as shown. Steam passes from the main chest through the ports f into the auxiliary chest C, and thence by the above-mentioned ports and passages to either 80 end of the main chest to operate upon the piston thereof and shift the valve, as will be well understood.

In working both the engines together the main valve A, having been brought to a closed 85 position, as before, is prevented from further movement by the position of the auxiliary valve B³, which is upon its seat covering the steam-passages a a'. When the engine No. 2 has arrived at the central position in its stroke, 90 it rocks the auxiliary valve B³ of engine No. 1 through the medium of its connections therewith, and the port n is put in communication with the port a and cove c and the port b, thus admitting steam to the main-valve piston of 95 engine No. 1. When the engine No. 1 is at the opposite end of its stroke, the valve B³ has been moved by engine No. 2 so as to bring the ports n' a' in communication with each other and with the cove c, while the steam is exhausted through ports h and d and passage g. When either engine is to be thrown out of op-

erative connection with the other, the lever E is shifted to carry the valve D of said engine from its seat, as shown in Fig. 2.

It will be seen that by the above-described construction of auxiliary valve I am enabled to secure the same result as by the more complicated and expensive construction set forth in the before-said patent to Hamilton.

Without limiting myself to the precise construction and arrangement of parts set forth, I claim—

1. In a duplex engine, the combination of auxiliary-valve chests having flat valve-faces and communicating with the main-valve chests through ports, flat-faced auxiliary valves fitted to the said valve-faces, to and from which they are adjustable, and provided with ports adapted to register with the aforesaid ports, and connections with the engines whereby the said auxiliary valves are rocked, substantially as set forth.

2. In a duplex engine, the combination of the auxiliary-valve chests having flat valve-

faces and communicating with the main valves through steam-ports, the flat valves B³, fitted to the said valve-faces and provided with steam-ports, and sliding and oscillating rods upon which the said valves are mounted, substantially as set forth.

3. In a duplex-engine, the combination of the auxiliary-valve chests having flat valve-faces perforated to form the steam-ports f, a, and a', the flat valves B³, fitted to the said valve-faces below the ports f and covering the ports a and a', and provided with the ports n and n', adapted to be brought to register with the ports a and a', and the sliding and oscillating rod upon which the valves are mounted, substantially as set forth.

In testimony whereof I have signed my name to this specification in the presence of two subscribing witnesses.

PERCY R. FOSTER.
